UNITED STATES PATENT OFFICE

REINHARD E. BARTELS, OF LYNN, MASSACHUSETTS; IDA M. BARTELS AND R. BURLEIGH BARTELS, EXECUTORS OF SAID REINHARD E. BARTELS, DECEASED

SHOE-SHANK STIFFENER

Application filed September 21, 1925. Serial No. 57,541.

Shoe shank stiffeners are sometimes fixed in shoes by means of rivets extending through the stiffeners and the soles, the heads of the rivets showing on the outer faces of the soles and imparting ornamental effects. It is necessary, however, to perforate the stiffeners to receive the rivets and as they are commonly formed of narrow metal strips they are greatly weakened by these perforations and liable to be broken when the shoes are in service.

With upwardly extending prongs 5 which may be partially cut from the material of the stiffener element 3 and bent upwardly. The prongs 5 are clinched down against the outer face of the stiffener element 3 having been placed in position on the inner face of the sole blank 1, rivets 2 and 4 in the sole blank 1 and stiffener element 3, the heads 7 of these rivets engaging the outer face of the sole blank and the shanks of the rivet are clinched down against the outer face of the stiffener element as by striking them with a hammer. While these rivets may be of any suitable description, the only one of which is perforated to receive the pronged and headed fasteners such as are rivets, the other being fixed to the first so as to be held in position in the shoe thereby reinforcing it throughout substantially its entire extent.

The present invention provides a construction of shank stiffener by which fastening rivets may be used without however so weakening the stiffener that it is liable to break in service. This is effected by forming the shank stiffener in two parts or laminations, one of which is perforated to receive the pronged and headed fasteners such as are commonly used for fastening together sheets of paper, may be employed. A fastener of this type is shown best in Figure 7 and comprises a narrow strip 10 of sheet metal folded over to form a flat head over which a circular piece of sheet metal 12 is crimped. The advantageous details and combinations of parts, reference may be had to the accompanying drawings in which

For a more complete understanding of this invention, together with further objects and advantages, reference may be had to the accompanying drawings in which

Figures 1 and 2 are perspective views of the two parts of the stiffener in condition to be attached to the sole.

Figure 3 is a similar fragmentary view of the sole perforated to receive the stiffener.

Figure 4 is a fragmentary longitudinal central section through the shank portion of the sole showing the two parts of the stiffener attached thereto in condition for the molding operation.

Figure 5 is a similar section showing the parts being molded.

Figure 6 is a fragmentary perspective of the complete stiffener as assembled with the sole and molded in condition to be incorporated in a shoe.

Figure 7 is a detail section on line 7—7 of Figure 4.

A flat sole blank as indicated at 1 in Figure 3 is perforated at 2 intermediate its ends for the reception of the rivets by which the stiffener is to be fixed thereto. A flat stiffener element 3, as shown in Figure 1, is provided with

A reinforcing strip 15, as shown in Figure 2, molded to a lateral curvature, and provided with openings 16 adjacent to opposite ends spaced to mate the prongs 5 is then placed over the stiffener element 3, its concave side being turned outwardly, and the prongs 5 are passed through the openings 16 and bent downwardly, as by striking them with a hammer against the outer face of the piece 15, as shown in Figures 4 and 6.

Next the combined sole blank and the reinforcing elements are molded to the proper longitudinal and lateral curvature of the shank portion of the shoe sole between dies indicated at 20 and 21 in Figure 5. The die 20 is provided with a convex lower edge, forming to the lateral curvature which it is desired to give the shank portion of the shoe which engages automatically in the concave face of the reinforcing element 15 thus tending to center the sole blank and the stiffeners

properly between the dies. Not only does this molding operation impart the lateral and longitudinal curvature to these parts, but it also tightens the engagement between the elements 3 and 15 so that there is no possibility of their becoming loose when the shoe is in service.

As the sole blank is flat when the stiffener is to be applied thereto, it is much easier to apply the element 3 thereto while this element also is in flat condition, as shown in Figure 1, than if it were molded to either the longitudinal or lateral curvature.

It will thus be seen that both of the elements of the stiffener are attached when in their best possible condition for the particular operations to which they are to be subjected, the flat element 3 engaging the flat sole blank and the element 15 being flat longitudinally but laterally curved so as to be easily engaged with the element 3 and yet have a lateral centering action on the assembled sole and stiffener elements so that they may be molded to their final configurations in an expeditious and accurate manner without particular attention being paid to the placing of the assembled parts in a molding press. The element 3 is directly attached to the sole while the element 15 is attached to the element 3 only and independently of the sole-attaching means of the element 3. The element 15 is thus imperforate for the major portion of its length and acts as a substantial reinforce for the perforated element 3.

While three apertures for rivets and a single prong adjacent to each end of the element 3 has been shown, it is of course evident that the number of rivets to be employed might be varied and that the number of prongs and their arrangement by which the reinforcing element is fixed to the element 3 may also be varied, and that various other changes and modifications might be made therein without departing from the spirit or scope of this invention as defined by the appended claims.

I claim:

1. The combination with a shoe sole, a perforated shank stiffener element, and a rivet passing through said perforation and attaching said element to said sole, of a reinforcing element overlying said stiffening element and rigidly fixed thereto only and independently of said rivet.
2. The combination with a shoe sole, a shank stiffener element perforated intermediate its ends and having prongs projecting therefrom adjacent to its ends, and rivets passing through said perforations and fixing said element to said sole, of a reinforcing element overlying said stiffening element and having openings to receive said prongs, the portions of said prongs extending through said openings being bent against the outer face of said reinforcing element to retain it in position.

3. The combination with a shoe sole and a shank stiffener element attached to said sole, of a reinforcing element overlying said stiffener element and rigidly fixed thereto only and independently of said sole attaching means.

4. The combination with a shoe sole and a shank stiffener element attached intermediate its ends to said sole, of a reinforcing element overlying said stiffener element and fixed thereto nearer to its ends than its attachment to said sole.

In testimony whereof I have affixed my signature.

REINHARD E. BARTELS.
